(57) **CLAIM**

The ornamental design for a storage caddy, as shown and described.

DESCRIPTION

FIG. 1 is an isometric view of a storage caddy in a first orientation;

FIG. 2 is a front side view of the storage caddy illustrated in FIG. 1 in the first orientation;

FIG. 3 is a rear side view of the storage caddy illustrated in FIG. 1 in the first orientation;

FIG. 4 is a side view of the storage caddy illustrated in FIG. 1 in the first orientation;

FIG. 5 is a side view, which is opposite the side view of FIG. 4, of the storage caddy illustrated in FIG. 1 in the first orientation;

FIG. 6 is a top side view of the storage caddy illustrated in FIG. 1 in the first orientation;

FIG. 7 is a bottom side view of the storage caddy illustrated in FIG. 1 in the first orientation;

FIG. 8 is an isometric view of a storage caddy illustrated in FIG. 1 in a second orientation;

FIG. 9 is a front side view of the storage caddy illustrated in FIG. 1 in the second orientation;

FIG. 10 is a rear side view of the storage caddy illustrated in FIG. 1 in the second orientation;

FIG. 11 is a side view of the storage caddy illustrated in FIG. 1 in the second orientation;

FIG. 12 is a side view, which is opposite the side view of FIG. 11, of the storage caddy illustrated in FIG. 1 in the second orientation;

FIG. 13 is a top side view of the storage caddy illustrated in FIG. 1 in the second orientation; and,

FIG. 14 is a bottom side view of the storage caddy illustrated in FIG. 1 in the second orientation.

The broken lines in the drawings form no part of the design to be patented.

1 Claim, 14 Drawing Sheets
